JET PROPULSION UNIT

Filed May 12, 1943

UNITED STATES PATENT OFFICE

2,588,532

JET PROPULSION UNIT

John Algot Johnson, Wauwatosa, Wis., assignor
to Allis-Chalmers Manufacturing Company,
Milwaukee, Wis., a corporation of Delaware

Application May 12, 1943, Serial No. 486,655

3 Claims. (Cl. 60—35.6)

1

This invention relates generally to power units and more particularly to jet propulsion apparatus for aircraft and other types of vehicles utilizing a propelling jet or jets formed by separate hot and cold gas streams.

An illustrative dual stream unit of the type hereinabove referred to is disclosed and claimed in my copending application Serial No. 484,159, filed April 23, 1943, now abandoned, and the primary object of this invention is to provide an improved dual or multiple stream jet propulsion unit effective to materially reduce the power requirements of the compressing apparatus employed and to materially increase the effective thrust of the propelling jet or jets.

Another object of this invention is to provide an improved dual or multiple stream jet propulsion unit which in addition to reducing the power requirements and/or increasing the effective thrust of the propelling jet or jets, makes possible a simplified and durable construction using lighter materials.

In accordance with this invention, the above stated objects may be accomplished in whole or in part by correlating and operatively interconnecting high and low pressure gas compressing apparatus, prime mover apparatus, and nozzle means to provide separate hot and cold gas conducting passages which connect the discharge portions of the high and low pressure compressing apparatus with said nozzle means and which are formed in part by a common heat exchanging wall structure intercoolingly surrounding or otherwise intercoolingly enclosing or partially enclosing the high pressure compressing apparatus in order to increase the temperature and thereby the thrust producing effectiveness of the cold gas stream, and in order to reduce the power required to drive the compressing apparatus by an amount greater than the increase in heat energy input necessary to raise the temperature of the hot gas stream to the same degree attained without the use of such an intercooling wall structure.

The invention accordingly consists of the various combinations of elements and arrangements of parts as is more fully set forth in the appended claims and in the detailed description, reference being had to the accompanying drawing, in which:

Fig. 1 schematically illustrates in longitudinal section a jet propulsion unit embodying the invention;

Fig. 2 is a transverse section taken on line II—II of Fig. 1; and

Fig. 3 is a transverse section taken on line III—III of Fig. 1.

2

Referring to the drawing, it is seen that the invention may be embodied in a unit comprising an axial flow compressor 1 having a low pressure section 2 and a high pressure section 3; an axial flow turbine 4 axially spaced from and drivingly connected with the adjacent end of the compressor 1 by means of shaft 6, an inner shell 7 surrounding shaft 6, an intermediate shell 8 surrounding and forming with the active blade carrying portion of the high pressure compressor section 3, with the inner shell 7 and with the active blade carrying portion of the turbine 4 an inner passage 9 including a plurality of fuel distributing nozzles 11 disposed therein between the discharge end of the compressor section 3 and the inlet end of the turbine 4, and an outer shell 12 surrounding and forming with the intermediate shell 8 an outer passage 13 receiving a portion of the air discharged from the low pressure compressor section 2; the remainder of the air compressed in the low pressure section 2 entering the high pressure section 3 in which it is further compressed and discharged into the inner passage 9.

25 The compressor end of the outer shell 12 extends forwardly beyond the low pressure compressor section 2 and forms with a coaxially extending cone-shaped casing 14 enclosing the adjacent shaft portion of the compressor 1, a forwardly facing inlet passage 16 through which air enters the active blade carrying portion of the low pressure section 2. The turbine end of the outer shell 12 extends rearwardly beyond the exhaust end of the turbine 4 and forms with a coaxially extending cone-shaped casing 17 a thrust producing nozzle structure embodying in this illustration only a single rearwardly directed expanding jet forming passage 18 combiningly received therein the hot gases issuing from the turbine 4 and the relatively cool gas flowing through the outer surrounding passage 13; the active blade carrying portion of the turbine 4 and the exhaust end thereof forming a continuation of and constituting the nozzle end of the inner passage 9.

The compressor end of the intermediate shell 8 terminates in or merges with a heat exchanger comprising a fluted or finned wall portion 19 forming in side-by-side relation (see Fig. 2) longitudinally extending and relatively narrow channel 21 through which flows a portion of the gas issuing from the low pressure portion or section 2; said portion being thus separated from the gas undergoing further compression in the high pressure portion or section 3. In other words, the high and low pressure compressing means, wheth-

er constructed and arranged in the partial series flow relation herein shown or otherwise, embodies a common heat exchanging wall structure separating the gas issuing from the low pressure compressing means from that undergoing compression in the high pressure compressing means, thereby increasing the temperature and the thrust producing effectiveness of the relatively cool low pressure stream and simultaneously intercooling the high pressure compressing means sufficiently to reduce the power required to drive said compressing means by an amount greater than the increase in heat energy input necessary to raise the temperature of the hot gas stream to the same degree attained without the use of the heat exchanging wall structure. The nozzle end of the intermediate shell 8 also terminates in or merges with a fluted portion 23 forming in side-by-side relation (see Fig. 3) relatively narrow alternate continuations 24 and 26 of the inner and outer passages 9 and 13, respectively; said continuations functioning to improve the thrust producing effectiveness of the combined streams as is more fully disclosed in applicant's aforementioned copending application. However, since this construction forms no part of the present invention, a further description of same is deemed unnecessary.

The compressor end of the shaft 6 and the adjacent end of the rotor of compressor 1 connected thereto are supported in a common bearing structure 27 which is in turn supported by a plurality of inwardly extending struts 28 carried by the adjacent portion of the inner shell 7. The forward or inlet end of the rotor of compressor 1 is supported in journal and thrust bearings 29 and 31, respectively, which are in turn supported by inwardly extending ribs or the like 32 and 33 carried by the cone-shaped shell 14. The turbine end of the shaft 6 and the adjacent end of the rotor of turbine 4 connected thereto are also supported in a common bearing structure 34 which is in turn supported by inwardly extending struts 36 carried by the adjacent end portion of the inner shell 7. Consequently, the compressor 1, turbine 4 and interconnecting shaft 6 are supported as a unit by three axially spaced bearings with the turbine disposed in overhung relation to the bearing structure 34, thereby presenting a simplified and compact arrangement.

In operation, the air entering the forwardly facing inlet passage 16 is first compressed to a predetermined degree in the low pressure section 2 and issues therefrom in two streams, one of which the inner stream in this case, enters the high pressure section 3 in which it undergoes further compression and issues therefrom into the combustion chamber portion of the passage 9, that is, the portion containing the fuel distributing nozzles 11, in which burning takes place, thereby highly heating the inner stream before it enters the turbine 4 from which it is discharged into the nozzle passage 18 and the other of which, the outer stream in this case, enters the outer passage 13 through which it flows directly into the nozzle passage 18 in which it is mixed with the hot gas stream issuing from the turbine 4, the resulting mixture being then expanded in the nozzle passage to produce a rearwardly directed propelling jet or blast having the velocity desired for a given wake efficiency, that is, the efficiency of the jet or blast as a propelling means.

The feature of separating the relatively cool

low pressure stream issuing from the compressing section or means 2 from that undergoing further compression in the high pressure compressing section or means 3 by a heat exchanging wall structure effective to increase the temperature and thereby the thrust producing effectiveness of the cool gas stream while intercooling the high pressure compressing means sufficiently to obtain a net gain in energy input results in an increase in both thermal efficiency and propulsive thrust. This improved result is obtained irrespective of whether the cool and hot gas streams are rapidly mixed and then expanded in the manner disclosed in my copending application hereinbefore identified and irrespective of whether the high and low pressure compressing means are constructed and arranged as herein shown and described or otherwise, since the only requirement in this respect is to separate the relatively cool gas stream issuing from a low pressure compressing means from that undergoing compression in a high pressure compressing means by a heat exchanging wall structure which is effective to produce the aforementioned improved results. In this connection, such a separating wall structure can be readily designed by anyone skilled in the art knowing the altitude at which the unit is to be operated, its translational velocity, and whether the temperature and pressure of the jet producing hot gas stream are increased or decreased and to what extent by the prime mover utilizing same, since from this information the temperature of the incoming air, the relative quantities undergoing compression in the high and low pressure compressing means and the ultimate temperatures and velocities of the thrust producing hot and cold gas streams can be determined.

The invention is applicable generally to jet propulsion apparatus utilizing a propelling jet or jets formed at least in part by separate streams discharged from high and low pressure compressing means irrespective of whether said streams are separately expanded to produce propelling blasts or jets or mixingly combined and then expanded to produce a single propelling jet or blast and irrespective of whether the prime mover means embodied in such apparatus is of the turbine, internal combustion engine or other gas utilizing type or combinations thereof; and it should therefore be understood that it is not intended to limit the invention to the exact details of construction herein shown and described, as various modifications within the scope of the appended claims may occur to persons skilled in the art.

It is claimed and desired to secure by Letters Patent:

1. A jet propulsion unit comprising a gas compressing means having a forwardly facing inlet and rearwardly discharging high and low pressure compressing portions, a turbine spaced from and drivingly connected with said compressing means, a combustion chamber interposed between and connecting the discharge of said high pressure compressing portion with the inlet of said turbine, a rearwardly directed thrust producing nozzle structure, means including said combustion chamber and turbine forming a first fluid confining passage connecting the discharge of said high pressure compressing portion with said nozzle structure, the major extent of the high pressure compressing portion being surrounded by a heat exchanging wall structure separating the gas issuing from the discharge of the low pressure

compressing portion from that undergoing further compression in the high pressure compressing portion, said heat exchanging wall structure abstracting heat from the gas undergoing further compression for substantially reducing the power required for driving said gas compressing means and increasing the total heat energy delivered to said nozzle structure, and an outer shell means forming with said heat exchanging wall structure and said turbine a second passage surrounding said combustion chamber and directly connecting the discharge of said low pressure compressing portion with said nozzle structure.

2. A jet propulsion unit comprising a gas compressing means having a forwardly facing inlet and rearwardly discharging high and low pressure compressing portions, a turbine coaxially spaced from and drivingly connected with said compressing means, a combustion chamber interposed between and connecting the discharge of said high pressure compressing portion with the inlet to said turbine, a coaxial, rearwardly directed thrust producing nozzle structure, means including said combustion chamber and turbine forming an inner fluid confining passage connecting the discharge of said high pressure compressing portion with said nozzle structure, and means, including a wall structure providing in side-by-side relation a coaxial series of longitudinally extending channels surrounding the major extent of the high pressure compressing portion and separating a portion of the gas issuing from the discharge of said low pressure compressing portion from that undergoing further compression in the high pressure portion, said wall structure abstracting heat from the gas undergoing further compression for substantially reducing the power required for driving said gas compressing means and thereby increasing the quantity of heat energy carried to said nozzle structure by the exhaust from said turbine and by the low pressure gas forming an outer surrounding passage directly connecting the discharge of said low pressure compressing portion with said nozzle structure.

3. A jet propulsion unit comprising in coaxial combination a gas compressing means having a forwardly facing inlet and rearwardly discharging high and low pressure compressing portions, a turbine spaced from and drivingly connected

with said compressing means, a combustion chamber defining means interposed between and directly connecting the discharge of said high pressure compressing portion with the inlet to said turbine, a rearwardly directed thrust producing nozzle structure, means including said combustion chamber defining means and turbine forming an inner fluid confining passage connecting the discharge of said high pressure compressing portion with said nozzle structure, the major extent of the high pressure compressing portion being surrounded by a radially finned wall structure separating the gas issuing from the discharge of the low pressure compressing portion from that undergoing further compression in the high pressure portion, said finned wall abstracting heat from the gas undergoing further compression for substantially reducing the power required for driving said gas compressing means whereby the unused power is delivered to the nozzle structure as an increased quantity of heat energy, and an outer shell means forming with said finned wall structure, said combustion chamber defining means and said turbine a surrounding passage directly connecting the discharge of said low pressure compressing portion with said nozzle structure.
